UNITED STATES PATENT OFFICE.

JOHN H. STONEMETZ, OF ERIE, PENNSYLVANIA.

TAPELESS SHEET-CONVEYER MECHANISM FOR PAPER-FOLDING MACHINES.

SPECIFICATION forming part of Letters Patent No. 355,353, dated January 4, 1887.

Application filed January 8, 1886. Serial No. 188,042. (No model.)

To all whom it may concern.

Be it known that I, JOHN H. STONEMETZ, a citizen of the United States, residing at Erie, in the county of Erie and State of Pennsylvania, have invented certain new and useful Improvements in Tapeless Sheet-Conveyer Mechanism for Paper-Folding Machines; and I do hereby declare the following to be a full, clear, and exact description of the invention, such as will enable others skilled in the art to which it appertains to make and use the same, reference being had to the accompanying drawing, and to the letters of reference marked theron, forming part of this specification.

My invention relates to sheet-conveying mechanism for paper-folding machines; and it consists in the improvements hereinafter set forth and explained.

My invention is illustrated in the accompanying drawing, in which the figure is a top or plan view of a paper-folding machine embodying my improvements.

In its general construction the folding-machine shown contains the features usually embodied in paper-folding machines of ordinary construction, the sheet being conveyed to the first set of rolls, A A, by means of ordinary conveyer-tapes B. For conveying the once-folded sheet to the second set of rolls, D D, I dispense with the carrier-tapes ordinarily used, and use spirally-fluted conveyer-rollers C, which are placed in the machine obliquely to the rolls D D, so that as the once-folded sheet leaves the first set of folding-rolls, A A, it is received upon the spiral rolls C C and carried to its proper place over the second set of rolls. The spiral flutes on the rolls acting upon the sheet on lines parallel with the folding-rolls D D, and the rolls C being located

obliquely to the line of travel of the sheet, the sheet cannot sag down between them. These oblique rolls are driven by means of shafts E along the sides of the folding-machine, (one of which, however, not being shown.) On the shafts E are beveled gears F, which intermesh with beveled gears G on the journals of the rollers C. However, the rollers C may be driven in any suitable and convenient manner.

For convenience, in the drawing I have shown but one set of spirally-fluted oblique conveyer-rolls in the machine; but these sheet-conveying rolls are equally applicable to any or all of the folding-rolls of the machine, so that there need be no carrier-tapes used on the machine, spirally-fluted conveyer-rolls being used in their stead.

Having thus described my invention so as to enable others skilled in the art to which it appertains to construct and use the same, what I claim as new, and desire to secure by Letters Patent of the United States, is—

1. In a paper folding machine, the combination, with folding-rolls of said machine, of spirally-fluted sheet-conveying rollers placed obliquely to such folding-rolls, substantially as set forth.

2. In combination with the folding-rolls of a paper-folding machine, a tapeless sheet-conveyer mechanism consisting of spirally-fluted rollers placed at an angle of substantially forty-five degrees to the folding-rolls of said machine, substantially as set forth.

In testimony whereof I affix my signature in presence of two witnesses.

JOHN H. STONEMETZ.
